**COMBINED BABY TROPHY AND COIN BANK
OR SIMILAR ARTICLE**

Fred Haussman, Lancaster, Tex.

Application October 27, 1955, Serial No. 38,601

Term of patent 14 years

(Cl. D34—11)

The single figure is a perspective view of a combined baby trophy and coin bank or similar article, showing my new design. The side and rear not shown have substantially the same appearance as the side and front shown in the figure.

I claim:

The ornamental design for a combined baby trophy and coin bank or similar article, as shown and described.
